UNITED STATES PATENT OFFICE.

HERBERT C. WELLER, OF TUSCOLA, ILLINOIS.

COLOR RHEOSTAT.

Application filed December 30, 1922. Serial No. 610,060.

This invention relates to a color rheostat or a color device for mixing, blending and shifting colors of electric lighting, and an object of the invention is to provide a device 5 of this nature by means of which electric lights of primary or original colors preferably, or any different colors, may be combined in intensities of various proportions through the introduction of different 10 amounts of resistance into the color circuits so that lighting effects of various colors will result.

Another object of this invention is to provide a device as specified which will keep 15 the light intensities of the various resultant color combinations the same, throughout or during and after the process of shifting.

A further object of this invention is to 20 provide a color rheostat or shifting device for electric lights which is particularly designed for laboratory use, for use in advertising, or in theaters, or for any purposes where it is desirable to shift electric lights 25 from one color to another, and one which will eliminate the necessity of shifting electric lights and mediums wherever different color effects are desired, and one which will give a relatively great variety of color combinations.

30 Another object of the invention is to provide a mechanism for automatically breaking electric circuits to all of the series of bulbs except two series which the operator desires to blend at any one time.

35 Other objects of the invention will appear in the following detailed description taken in connection with the accompanying drawings wherein:—

Fig. 1 is a diagrammatic view of the 40 color rheostat, and the circuits embodied therein.

Fig. 2 is a vertical section through the rheostat taken on the line 2—2 of Fig. 1.

Fig. 3 is a horizontal section taken on the 45 line 3—3 of Fig. 2.

Fig. 4 is a face view of the rheostat.

Referring more particularly to the drawings, and with particular reference to Fig. 1 of the drawings, the improved color rheostat comprises a plurality of conductive contacts C¹ to C¹⁶ inclusive which are connected to each other by resistance coils R¹ to R¹⁶ inclusive. The contacts C¹ to C¹⁶ inclusive are divided in series and these series of contacts are connected by suitable

conducting wires to rows of electric incandescent bulbs, preferably, of primary colors. For example, the contact C¹ is connected to the series of light bulbs B¹ through conductor L^{1a}, L^{1b}, 48, switch 46, conductor 47, and line wire L¹. The contact C⁵ is connected to the series of light bulbs B² through conductor L^{2a}, L^{2b}, 48, switch 46, conductor 47, and line wire L². The contact C⁹ is connected in series with the light bulbs B³ by 60 the conductors L^{3a}, L^{3b}, 48, switch 46, conductor 47, and line wire L³ while the contact C¹³ is connected in series with the light bulbs B⁴ by conductors L^{4a}, L^{4b}, 48, switch 46, conductor 47, and line wire L⁴. The various series B¹, B², B³ and B⁴ are connected in circuit with one pole of a generator, dynamo, or other suitable power source 20. The opposite pole of the power source 20 is connected by a wire G¹ to a disc 70 75 21 of suitable conductive material, which is supported by a sleeve 22 of insulation. The sleeve 22 of insulation is mounted upon the post 23 of the housing 24 of the rheostat. The disc 21 is in turn connected by 80 resistance coils 25 and 26 to the contacts T¹ and T² of the inner circle of contacts, T¹ to T¹⁶ inclusive. The various contacts C¹ to C¹⁶ and T¹ to T¹⁶ are supported within 85 the housing 24 and are insulated from each other and from the housing by suitable insulation as shown at 27 of Fig. 2. The contacts T¹, T², T³ and T¹³ are connected in series by suitable conducting wires 28, as clearly shown in Fig. 1 of the drawings, 90 these contacts corresponding to the contacts C¹, C⁵, C⁹ and C¹³, which are connected to the series of electric light bulbs. The alternate contacts of the inner T circle of contacts are connected to each other by 95 wires 29, namely the contacts T², T⁴, T⁶, T⁸, T¹⁰, T¹², T¹⁴ and T¹⁶ connected by the wires 29. The contacts T³, T⁷, T¹¹ and T¹⁵ are connected to the disc 21 by suitable connecting wires 30.

A switch arm 31 is rotatably carried by the post 23 and comprises an arm 32 which is adapted to engage any one of the outer circle of contacts C¹ to C¹⁶, and an arm 33 which is adapted to contact with any one of 105 the inner circle of contacts T¹ to T¹⁶. A suitable thumb nut 34 is provided for rotating the switch arm 31 and an indicating hand 35 is carried by the thumb nut 34 and is adapted to cooperate with graduations 36 110

on a dial 37 for indicating the position of the switch arm 31 and consequently indicating the various contacts of the series in active connection with the respective series of light bulbs and power source 20.

It is to be understood that the contacts may be made in any desired number, and that any desired number of series of light bulbs may be used, without departing from the spirit of this invention, and that the light bulbs are preferably, of the various primary colors so that by movement of the pointer 31 various color effects may be obtained by variation of the resistance through the series of bulbs, and by closing a circuit through certain of the series.

In following out one of the circuits, namely the one shown in operative position in Fig. 1 of the drawings, it will be seen that the current will flow from the dynamo or current source 20, through the wire G^1 to the disc 21, from the disc 21 through the resistance 26 to the contact T^2 and through the wires 29 and the respective contacts to the contact T^{10} , which is engaged by the arm 33. The current will flow through the arm 33, to the contact C^2 which is engaged by the arm 32 of the switch arm 31 and from the contact C^2 through the resistance R^1 to the contact C^1 and out through the various conductors and switch 46 into and through the series of bulbs B^1 , returning to the power source or generator 20. It will be noted that there is only a single resistance, namely the resistance R^1 between the arm 32 of the pointer and the outlet wire L^1 , while there are three resistances, namely the resistances R^2 , R^3 and R^4 between the arm 32 and the outlet wire L^2 to the series of lights B^2 , thereby a greater amount of current will flow through the series of lights B^1 than through the lights B^2 making the former lights brighter and consequently providing a color effect in which the primary colors of the bulbs B^1 will predominate.

It will be seen that by shifting the pointer 31, the amount of resistance through the various circuits may be varied to make the color of any one of the series of light bulbs 50 of the predominating color in the color effect produced.

The mechanism for automatically breaking the circuits to all of the series of bulbs other than the two which the operator desires to blend at any one time lies without the series of contacts C^1 to C^{16} respectively and consists of a plurality of conductors such as L^{1a} , L^{2a} , L^{3a} and L^{4a} . The conductor L^{1a} connects the contact C^1 to the semi-circular conductor L^{1b} . The conductor L^{2a} connects the contact C^5 to the substantially semi-circular conductor L^{2b} , while the conductors L^{3a} and L^{4a} connect the contacts C^9 and C^{13} to the semicircular conductors L^{3b} and L^{4b} respectively, as clearly shown in Fig. 1 of

the drawings. Conductors L^{1c} , L^{2c} , L^{3c} and L^{4c} are disposed in parallel relation to the conductors L^{1b} , L^{2b} , L^{3b} and L^{4b} respectively and are insulated therefrom by means of suitable strips 40 of insulation, which strips are carried by the conductor supporting ribs 41 formed on the casing 24, as clearly shown in Fig. 2 of the drawings. The arm or end 32 of the pointer 31 has bridging contacts 43 and 44 carried thereby which are insulated from the pointer by suitable blocks 45 of insulation.

When the end 32 of the pointer 31 is not above or passing over L^{1b} and L^{1c} the circuit from the contact C^1 to the line L^1 is broken but when the end 32 is over or passing over the conductors L^{1b} and L^{1c} connection is made by means of the bridge or riding contacts 44, thus the current will be cut off between them or prevented from passing to L^3 and L^4 but will be permitted to pass to L^1 and L^2 and when the current is permitted to pass to any two series of the light bulbs, no current will be permitted to pass to the remaining set or sets of bulbs.

Switches 46 are provided for connecting the respective conductors L^{1b} and L^{1c} , L^{2b} and L^{2c} , L^{3b} and L^{3c} , and L^{4b} and L^{4c} respectively by means of conducting wires 47 and 48 and when it is desired to permit the energizing of more than two sets of bulbs the parallel pairs of conductors may be connected by the respective switch structures.

A switch structure 50 is provided by operation of which the current can be made to divide between only the lines L^1 and L^3 or between only L^2 and L^4 and if it is so desired there may be a switch (not shown) by which all the lines can be opened or closed at one time. without the use of the bridge or riding contacts 43 and 44, such switch would preferably be located to establish connection between the L^b and L^c conductors.

If it is so desired, a dimmer of approved type, which may take the form of either a resistance or an impedance coil, depending upon whether the circuit is direct or alternating current may be connected in a shunt circuit with the wire G^1 , by the switch structure 49 so as to permit varying of the intensity of any one combination or color effect at any time; also if it is desired to make the various shades or colors lighter, this may be done by installing a separate circuit or series of white light bulbs as indicated at 51, in combination with the dimmer structure 52 in parallel to the color series B^1 , B^2 , B^3 and B^4 and vary the brightness of said white lights at will by operation of the dimmer structure.

It is, of course, to be understood that the invention may be constructed in other manners and the parts associated in different

relations, and therefore, I do not desire to be limited in any manner except as set forth in the claims hereunto appended.

Having thus described my invention what I claim is:—

1. In a color rheostat a plurality of contacts, conductors connecting certain contacts in groups, resistance elements connecting other contacts in groups, a plurality of contact strips and a contact arm for bridging the contacts and contact strips in various combinations.
2. A color rheostat comprising an inner series of contacts, an outer series of contacts, a plurality of contact strips, resistance elements arranged between the outer contacts, conductors connecting the inner contacts in various groups and means for taking current from the inner contacts passing it to the outer contacts and further bridging certain of said contact strips.
3. A color rheostat comprising an inner series of contacts, an outer series of contacts, a plurality of contact strips, resistance elements arranged between the outer contacts, conductors connecting the inner contacts in various groups and means for taking current from the inner contacts passing it to the outer contacts and further bridging certain of said contact strips, and individual switches for the contact strips.
4. In a color rheostat, an outer circle of spaced contacts, resistance coils connecting said contacts, a plurality of series of light bulbs, series of said contacts connected to the respective series of light bulbs, an inner set of contacts, certain of said inner set of contacts connected in sets, a power source, and adjustable means establishing connection between said inner and outer sets of contacts, power source and series of light bulbs.
5. In a color rheostat, an outer circle of spaced contacts, resistance coils connecting said contacts, a plurality of series of light bulbs, series of said contacts connected to the respective series of light bulbs, an inner set of contacts, certain of said inner set of contacts connected in sets, a power source, a movable switch arm engaging the series of the contacts in said inner and outer sets of contacts, said pointer movable to regulate the resistance to energizing current flowing to the respective series of light bulbs.
6. In a color rheostat, an outer circle of spaced contacts, resistance coils connecting said contacts, a plurality of series of light bulbs, series of said contacts connected to the respective series of light bulbs, an inner set of contacts, certain of said inner set of contacts connected in sets, a power source, a movable switch arm engaging the series of the contacts in said inner and outer sets of contacts, said pointer movable to regulate the resistance to energizing current flowing to the respective series of light bulbs, and

means for varying the intensity of the energizing current flowing to said contacts.

7. In a color rheostat, the combination with a plurality of series of light bulbs, and a source of energizing current, of a plurality of contacts, resistance coils connecting said contacts, a movable circuit closer movable over said contacts to proportionally vary the resistance to energizing current flowing to the respective series of light bulbs, and means for automatically breaking the circuit to all other series of bulbs other than two series which it is desired to blend.

8. In a color rheostat, the combination with a plurality of series of light bulbs, and a source of energizing current, of a plurality of contacts, resistance coils connecting said contacts, a movable circuit closer movable over said contacts to proportionally vary the resistance to energizing current flowing to the respective series of light bulbs, and means for automatically breaking the circuit to all other series of bulbs other than two series which it is desired to blend, and a plurality of switches to permit energizing of the light bulbs irrespective of said last named means.

9. A color rheostat including circularly disposed contacts, resistance units disposed concentrically with respect to the contacts, elements connecting said resistance units together providing a continuous circuit between the units, contact strips arranged concentrically with respect to the resistance units, means providing a connection between certain of the contact strips and the elements, means for connecting the contacts to one side of an electrical circuit, means for connecting the other of the contact strips to the other side of the electrical circuit, and a member movable over said elements and said contacts and bridging said contact strips.

10. A color rheostat including circularly disposed contacts, resistance units disposed concentrically with respect to the contacts, elements connecting said resistance units together providing a continuous circuit between the units, contact strips arranged concentrically with respect to the resistance units, means providing a connection between certain of the contact strips and the elements, means for connecting the contacts to one side of an electrical circuit, means for connecting the other of the contact strips to the other side of the electrical circuit, a member movable over said elements and said contacts and bridging said contact strips, means for optionally connecting said certain contact strips to the circuit connecting means of the other of the contact strips, and means for moving said member.

11. A color rheostat including circularly

4

disposed contacts, resistance units disposed concentrically with respect to the contacts, elements connecting said resistance units together providing a continuous circuit between the units, contact strips arranged concentrically with respect to the resistance units, means providing a connection between certain of the contact strips and the elements, resistance elements having connection to certain of the contacts, means for connecting the resistance elements to one side of an electrical circuit, means for connect-

ing certain of said contacts in groups, other resistance elements, means for optionally connecting the other resistance elements in circuit with the circuit connecting means of the first mentioned resistance elements, means for connecting the other of the contact strips to the other side of the electrical circuit, and a member movable over said elements and said contacts and bridging said contact strips.

In testimony whereof I affix my signature.
HERBERT C. WELLER.
